UNITED STATES PATENT OFFICE.

ZEBEDEE MACOMBER, OF BEDFORD, ASSIGNOR TO THE UNION MANUFACTURING COMPANY, OF BATTLE CREEK, MICHIGAN.

THRASHING-MACHINE TOOTH.

SPECIFICATION forming part of Letters Patent No. 472,131, dated April 5, 1892.

Application filed November 8, 1891. Serial No. 410,805. (No model.)

To all whom it may concern:

Be it known that I, ZEBEDEE MACOMBER, a citizen of the United States, residing at Bedford, county of Calhoun, State of Michigan, 5 have invented a new and useful Thrashing-Machine Tooth, of which the following is a specification.

This invention relates to detachable teeth for the cylinders and concaves of thrashing-machines.

The object of this invention is to construct a tooth which will facilitate the scouring of the heads of straw and the separation of the grain therefrom without crushing or breaking 15 the same and at the same time can be connected with old cylinders and concaves already in use in order to provide them with teeth.

Other objects will appear in the description 20 and in the claims.

In the drawings forming a part of this specification, Figure 1 is a side elevation of one of the teeth to be attached to the cylinder; Fig. 2, an elevation of Fig. 1, looking 25 from a point at the right. Fig. 3 is a side elevation of a tooth for attachment to the concave; and Fig. 4 is a section on line 2 2 in Figs. 1 and 2, looking from a point above.

Referring to the lettered parts of the drawings, A is a tooth made of a suitable form, provided with the ordinary screw-threaded portion B, and which is secured in holes in the cylinder or concave at the base of the tooth, and at the juncture of the pendent portion are two laterally-extending fins s s, the bottom portion of which fins comes against the surface of the cylinder or concave, as the case may be, and thus the back fins act as a brace to prevent the teeth from canting in that direction; but so far as these back fins are concerned, while they are beneficial as a brace, they may be dispensed with so far as the front fins are concerned. In Fig. 1 the bottom surface of the fins is adapted to fit against the surface of the bars of the cylinder, which bars are comparatively flat, while in Fig. 3 the bottom surface of the fins s s is slightly convex to fit the concave surface of the concave cylinder. No cylinders and concaves are here 45 shown, but will be readily understood by those versed in the art, it being understood, of course,

that the pendent portions B pass into said parts and are held by a nut on the lower threaded end of said pendent portions. These fins s s are integral with the teeth A and their 55 upper periphery curves or slants downward from their upper point of connection with said teeth, and they also are made rounding or slanted laterally each way from said periphery, as indicated at e in Figs. 1 and 4, so 60 as to present an edge v, past the side of which the straw passes when coming in contact with the said surface e. The advantage of this over some other constructions in which the base of the teeth have been angular or the 65 teeth themselves have been angular is that in the present instance the grain is not broken, as in said other styles, but is successfully rubbed out of the heads of the grain, since the fins of the cylinder-teeth come in sufficiently close relation with the fins of the teeth of the "concave" to rub the heads of the grain between the rounding surfaces of the fins of the teeth without crushing the same. 70

Some concaves have heretofore been provided with rounded or oval projections, which are integral with the surface of said concave and between which projections the tooth was inserted. 75

By means of my tooth in Fig. 3, with its integral fins, a concave not having the integral projections may be provided with my tooth, thus imparting to it all the benefits of these projections, of which the fins s s are a substitute, without necessitating the manufacture 85 of a new concave in old machines which are not provided with said projections. 80

My tooth in Fig. 1, with its integral fins, can be attached to the cylinder of new machines or to old cylinders, thus providing the bars 90 around the periphery of the cylinders with teeth having these fins s s. This will be found very desirable, since the bars of the cylinders which bear the teeth are made of wrought-iron and could not be provided with the said 95 projections representing the fins by casting them as the concaves are cast.

At z z, Figs. 1 and 3, the sides of the tooth A near and where it joins the fins s s are cut or beveled away, so as to extend the rounding 100 surface e up onto said tooth, thus depriving it of any angularity at the point where the

grain might otherwise be cracked but for said cut-away portion. While this cut-away portion *z* is deemed to be beneficial, in some instances it might not be necessary. Another 5 point of utility of these cut-away portions *z* and fins *s* on the front side of the tooth will be seen in the operation of the machine. The grain being fed into the machine, the teeth will force the grain down upon the fins, and 10 they in turn will cause it to lift up and settle back against the cut-away portion *z*, so that unthrashed grain will pass between the fins and below the teeth A.

For the reasons before given these teeth 15 may become a commodity in trade for supplying old machines, or when used in new machines they may be readily detached from the cylinder or concave and new teeth supplied.

20 Having thus described my invention, what I claim as new, and desire to secure by Letters Patent of the United States, is—

1. A thrashing-tooth provided at that point where the tooth joins its shank with the in-

tegral fins projecting in opposite directions 25 from each other, the upper edge of said fins curving or slanting downward to the cylinder or concave to which they are attached, said fins also being rounded or beveled on each side backward from their upper edge, and 30 the tooth above said edge having the beveled cut-away portion, substantially as set forth.

2. A thrashing-tooth provided with an integral fin on its front side, the upper edge of said fin being curved downward from the 35 tooth at its point of contact with the cylinder or concave and rounded or beveled backward on each side from its upper edge, said tooth just above the upper edge of said fin having the beveled cut-away portion, substantially 40 as set forth.

In testimony to the foregoing I have hereunto subscribed my name in the presence of two witnesses.

ZEBEDEE MACOMBER.
